(57) **CLAIM**

The ornamental design for a sensor, as shown and described.

DESCRIPTION

FIG. 1 is a top perspective view of a sensor according to our new design;

FIG. 2 is a bottom perspective of the sensor of FIG. 1;
FIG. 3 is front elevational view of the sensor of FIG. 1;
FIG. 4 is rear elevational view of the sensor of FIG. 1;
FIG. 5 is left side view of the sensor of FIG. 1;
FIG. 6 is right side view of the sensor of FIG. 1;
FIG. 7 is a top plan view of the sensor of FIG. 1; and,
FIG. 8 is a bottom plan view of the sensor of FIG. 1.
The broken lines shown in FIGS. 1 through 8 indicate portions of the sensor that form no part of the claimed design.
